PLANIMETER FOR COMPUTING FORCES

Application filed April 6, 1929, Serial No. 353,108, and in Germany December 29, 1927.

The present invention relates to a device which makes it possible to solve, mechanically, integrals of the form $\int r \sin \omega d\omega$, wherein the quantity r denotes the distance 5 of any point P from the origin of a rectangular system of coordinates and ω the angle between the line $O-P$ and one of the axes of the said system of coordinates. Such integrals occur, for instance, in calculating 10 the gravitation of bodies of any shape, but the device forming the object of the invention may, of course, be used for any other purpose desired, wherein integrals of the type mentioned must be evaluated.

15 The drawings show by way of example a number of embodiments of the invention, wherein

Figures 1 and 2 are diagrammatic sketches serving to explain the different principles of 20 construction of the device,

Fig. 2a is a side view, partly in section, showing a detail of Fig. 2,

Fig. 2b is a plan view of the device shown by Fig. 2a,

25 Fig. 3 is a plan view of a practical embodiment of the invention constructed in accordance with the principles shown in Fig. 1,

Fig. 4 is a side elevation, partly broken away, of Fig. 3,

30 Fig. 5 shows another practical embodiment constructed in accordance with the principle of Fig. 2 in side elevation and partly in section, and

Fig. 6 is a plan view of the device shown 35 by Fig. 5.

In Fig. 1, k denotes the sectional area of any body of any position and any extent. That sectional area must be supposed to be very small in proportion to the length of 40 that body. The point O may be assumed as representing the origin of a coordinate system, the X - and Z -axes of which lie in the plane of the sheet of drawing, whereas the Y -axis extends parallel to the greatest longitudinal extent of the respective body.

On a rotary axle passing through the point O in the direction of the vertical Y -axis is fastened at its centre a circular disk 33, and connected with said axle is also one end of an arm 34 on which a slide 30

bearing a tracing pin P can be shifted. A bar 35 is so coupled with said pin that when this latter is moved along the boundary line of any desired figure said bar is always guided parallel to the X -axis. The bar 35 55 carries a roll 36, viz the integrating roll, which contacts with the disk 33 either below or above the Z -axis, and the axis of rotation of which lies parallel to the Z -axis. If the tracing pin P is shifted along the figure from the position P to the position P_1 , the disk which, as stated, is affixed to the same axle to which also the arm 34 is secured is turned through the angle $d\omega$. Owing to this turning the roll 36 is developed by as 60 much as corresponds to the amount $r \sin \omega d\omega$. If the radius of the roll 36 is equal to b and to the angular part rotation a , then its entire development when being moved around the figure K is 65

$$b(a - a_1) = \int r \sin \omega d\omega$$

which represents, apart from the constant, which may be chosen as desired, the sought gravity in the point O .

In order to allow of the greatest possible accuracy of ascertainment of the gravity from the body 1 in the point O it is desirable for this purpose to choose the scale of the Figure K which represents the body as great 75 so as possible, but in order to prevent the circular disk 33 in this case from being of excessive size, the device is preferably designed in the manner shown in Fig. 2.

In this constructional form the circular 85 disk 33^a which is attached to a vertical axle extending through the O -point in the same manner as has been described with respect to the disk 33 of Fig. 1 is independent of the scale of the Figure K' and is only small in 90 comparison therewith. There is also in this case a tracing arm 42^a secured to said vertical axle, and extending to both sides from said axle. A slide 30^a can be shifted on said arm, and a tracing pin P is affixed to this 95 slide, all this practically as in Fig. 1. On that part of the arm 42 which extends beyond the point O is provided another slide P' which is connected with the slide P in such a manner that when the slide 30^a is 100

shifted along the arm 42^a the distance of the slide O' from the point O changes in a smaller proportion than that relating to the distance between the tracing pin P and the point O. For this purpose the construction illustrated in Figs. 2a and 2b may be used. As seen from these figures, a vertical axle 59 is supported on the arm 42^a, which carries the slide 30^a with the tracing pin P and the 10 slide 30^b carrying the member P'. The point of the arm 42^a, at which the axle 59 is supported, corresponds to the point O in Fig. 2. On the axle 59, two rolls 54 and 55 are rotatably mounted, the rolls being rigidly connected with each other. The roll 54 is connected with the axle 59 by means of a spiral spring 54^a. This spring is wound in such a manner that it has the tendency to wind the cord 64, which is connected with an 20 extension 30^c of the slide 30^a around the circumference of the roll 54. Around the roll 55, a second cord 65 is wound, the other end of which is connected with an extension P² of the slide 30^b. This slide 30^b is, on the 25 other hand, connected with the adjacent end of the arm 42^a by means of a helical spring 56. Therefore, this spring has the tendency to draw the slide 30^b away from the axle 59 and to unwind the cord 65 from the roll 55. 30 If the slide 30^a, carrying the tracing pin P, is shifted on the arm 42^a in such a manner that the distance between the pin P and the axle 59 increases, then the roll 54 is rotated by the cord 64 against the action of the 35 spring 54^a. The roll 55 is, therefore, also rotated through the same angle and the slide 30^b is shifted on the arm 42^a under the action of the spring 56 in such a manner that its distance from the axle 59 increases. 40 Inversely, if the slide 30^a is shifted on the arm 42^a, so as to approach the axle 59, then the spring 54^a, which is stronger than the spring 56, releases and effects a rotation of the rolls 54 and 55, whereby the cord 64 is 45 wound around the circumference of the roll 54, while the cord 65 is wound around the circumference of the roll 55 against the action of the spring 56. This slide 30^b is, therefore, shifted, so as to approach the axle 59. The lengths of the paths, which the two 50 slides 30^a and 30^b are traversing, correspond to the parts of the circumferences of the rolls 54 and 55, from which the cords 64 and 65 have been unwound, or on which the 55 cords have been wound. The lengths of the cords 64 and 65 are such that the points defined by the pins P and P' would reach the center of the axle 59 at the same time and, therefore, the proportion between the distances of the points P and P' from the center of the axle 59 is always the same as the proportion between the radii of the two rolls 54 and 55. If, therefore, the distance between the pin P and the point O is = r, 60 the slide P' will always be kept at a dis-

tance from the point O which is = c.r, in which equation c denotes a factor of proportionality which must be so chosen that the point P' cannot leave the disk. The slide P' is connected with a ledge 44^a to which is attached a roll 45^a. These members are equivalents to the members 35 and 36 in Fig. 1 and are arranged in the same manner as in this figure. When this device is employed, upon moving the tracing pin P round the figure K the desired integral is obtained in the proportion c, viz., $c \int r \sin \omega d\omega$.

With the constructional form shown in Fig. 2 the slide P', or the ledge 44^a and the roll 45^a, may be arranged, if desired, on the other side of O, that is to say, on the same side as the slide 30, without any change in the manner of operation of the device.

In Figs. 3 and 4 the details of an apparatus designed and operating according to the principle disclosed in Fig. 1 are shown. Figure 3 is a plan of this apparatus and Figure 4 a transverse section therethrough. 40 denotes a table provided with a bore located in the point O. Through this bore extends an axle 40^a which is firmly connected with a circular disk 41 located below said table. To the upper end of said axle is affixed the tracing arm 42 which bears a radially shiftable sleeve 43 that is provided with the tracing pin P. The arm 42 and the disk 41 are rigidly connected with one another by means of the axle 40^a so that they always turn through the same angle. Parallel to the X-axis a double-ledge 44 is arranged and guided along the righthand and the lefthand edge or rim of the table. The double-ledge consists of two parallel ledges which are rigidly connected with one another but are so arranged with respect to the table 40 that one of them is located above the table, the other below the same. The upper of these ledges is provided with a longitudinal guide slot and is coupled with the arm 42 by means of the pin P which extends through said slot. The lower ledge bears the integration roll 45 which contacts with the circular disk 41. The axle 45^a of said roll is supported in bearings 46 in the point O, as well as at the rim of the table, parallel with the Z-axis of the coordinate system.

When moving the tracing pin round the figure K² which represents the sectional area of the body in the earth the integration roll 45 is shifted by means of the guide slot of the ledge 44 in the direction of the Z-axis so that its distance from the axis of rotation in the point O is always $r \sin \omega$, in which formula r is = OP. On the axle 45^a of said roll 45 a counting disk 47 is affixed near the rim of the table, this disk permitting to read, with the aid of a vernier N, the rotation of the integration roll 45 which states the value of the integral.

$$\int r \sin \omega d\omega$$

and, therefore, also the value of the force of gravity of the body K² in the point O.

5 In the modification shown in Figs. 5 and 6 the principle is that disclosed in Fig. 2. In these figures 38 denotes a table, and 57 and 57^a are two spaced parallel plates arranged above said table and secured to it by a suitably shaped bracket 39. The two plates are firmly connected with one another by bolts 58. The plate 57^a bears a bearing 48 in which is supported an axle 59 to which is affixed the circular disk 33^a which contacts with a roll 45^a, viz. with the integration roll. This roll can be shifted on a shaft 60 with which it is coupled by means of feather and groove. The shaft 60 is supported in bearings 61 and 61^a and extends in the direction of the Z-axis. At one end of this shaft a counting disk 62 is provided which indicates the rotation of the integration roll; the rotation can be read off with the aid of a vernier 63 affixed to the bearing 61^a. The roll 45^a is attached 20 to a ledge 50 which is connected in turn with another ledge 50^a arranged parallel to the ledge 50. These two ledges lie always parallel to the X-axis and are guided by sleeves 51 which are shiftable on rods 52 of circular 25 transverse section. To the axle 59 of the circular disk is affixed the tracing arm 42^a which bears a slide 30^a with the tracing pin P, as well as a slide 30^b having a bolt P'. This bolt is guided in the slot 50^b of the lower 30 ledge 50^a.

From the slide 30^a a cord passes to a drum 54 supported loosely upon the axle 59 and subjected centrally to the action of a spring so that when the slide 30^a is shifted in the 40 direction toward the point O of the axle 59 the cord is wound upon said drum. Above that drum another drum 55 having a smaller radius is located, and is firmly connected with the first-mentioned drum. From the drum 45 55 a cord 65 extends to the slide 50^b which is subjected to the action of a spring 56, the other end of which is affixed to the tracing arm 42^a.

When the tracing pin P is moved with the 50 slide 30^a in the direction toward the point O of the axle 59, the cord 64 is wound upon the drum 54, and the cord 65 coming from the slide 30^b is wound upon the drum 55 whereby this slide is drawn toward the point O and the integration roll 45^a is shifted in the direction of the Z-axis. The turning movement of the tracing arm 42^a and, thus, also of the circular disk 33^a causes the roll 45^a to turn by a value

$$c \int r \sin \omega d\omega$$

60 in which r denotes the line OP, and ω denotes the angle between the arm 42^a and the X-axis.

The diameter of the drums 54 and 55 is so chosen, as are also the two portions of the 65 tracing arm 53, that the shifting of the bolt

P₁ with the slide 30^b takes place in proportion to the distance of the tracing pin P.

I claim:—

1. A calculating device for evaluating the integral $\int r \sin \omega d\omega$, especially for computing the force of gravity for a predetermined point, comprising, in combination, a tracing arm carrying a tracing pin and a circular disk rotatable together around a fixed point; an integration roll contacting with said disk; an axle bearing said roll; and means slidably arranged on said arm for guiding said roll on its axle in such a manner that its distance from the said fixed point always corresponds to the vertical distance between said tracing pin and a line crossing the said fixed point in a direction perpendicular to the axle of said integration roll.

2. A calculating device for evaluating the integral $\int r \sin \omega d\omega$, especially for computing the force of gravity for a predetermined point, comprising, in combination, a tracing arm carrying a tracing pin and a circular disk rotatable together around a fixed point; a point-forming member shiftable arranged on said tracing arm; an integration roll contacting with said disk; an axle bearing said roll, said roll being rotatable on said axle and means whereby it is so guided thereon that its distance from the fixed point corresponds to the vertical distance between said above named point-forming member which is shiftable on said tracing arm and a line crossing said fixed point in a direction perpendicular to the axle of the integration roll; and a coupling between said point-forming member and said tracing pin, the coupling being so designed that the distance between the said member and said fixed point is always proportional to the distance between the said tracing pin and the said fixed point.

3. A calculating device for evaluating the integral $\int r \sin \omega d\omega$, especially for computing the force of gravity for a predetermined point, comprising, in combination, a table; a tracing arm and a circular disk rotatable below said table around a fixed point, said tracing arm being arranged above the table and firmly connected with said disk; an integration roll; a member arranged on said arm to shift said roll; a double ledge, of which one ledge is located above the table and the other below the table; said integration roll being supported in the lower member of said double ledge; and means for guiding said ledge in a direction parallel to the axle of the said integration roll.

In testimony whereof I affix my signature.
WILHELM SCHWEYDAR.
